UNITED STATES PATENT OFFICE.

ALEC J. GERRARD AND PARVIN WRIGHT, OF CHICAGO, ILLINOIS; SAID WRIGHT
ASSIGNOR TO SAID GERRARD.

WIRE-TWISTING MACHINE.

Application filed April 5, 1920. Serial No. 371,368.

This invention relates to wire tying machines and has for its object to provide a machine of this character which will be comparatively inexpensive to manufacture and 5 more efficient in action than those heretofore proposed.

With these and other objects in view the invention consists in the novel details of construction and combinations of parts, more 10 fully hereinafter disclosed and particularly pointed out in the claims.

Referring to the accompanying drawings forming a part of this specification in which like numerals designate like parts in all the 15 views:—

Figure 1 is a diagrammatic elevational view of a machine made in accordance with this invention;

Figure 2 is a fragmentary view of a modified form of wire cutting mechanism;

Figure 3 is a sectional view of the parts shown in Figure 2;

Figure 3^a is a detail view of the wire holding hook and its coacting parts;

Figure 4 is a partially sectional plan view of the parts shown in Figure 1;

Figure 5 shows views of the flattened end of the tying wire;

Figure 6 is a diagrammatic sectional view 30 showing the wire tensioning mechanism and its coacting parts;

Figure 7 is a view on the line 7—7 of Figure 6 looking in the direction of the arrows;

Figure 8 is a view on the line 8—8 of Figure 6 looking in the direction of the arrows;

Figure 9 represents a wire holding post; and

Figure 10 is a sectional view taken on the line 10—10 of Figure 6 looking in the direction of the arrows.

1 indicates any suitable frame work, provided with the extension 2 constituting a handle, 3 a main operating shaft carrying the spiral gear 4, meshing with the gear 5, having the wire tensioning slotted shaft 6, and 7 represents a cylinder also carried by the shaft 3. 8 indicates a gear rigid with 45 said cylinder 7 and shaft 3, meshing with the gear 9, having the bearings 10. The frame 1 is provided with the forwardly extending foot or lug 11, and also with the member or bracket 13, secured thereto as

at 14, and provided with the forwardly extending lug 12.

The lugs 11 and 12 are each provided with a slot 15 with which slots 16 in the bearings 10, and the slot 17 in the gear 9, are adapted to register, as will be clear from Figs. 1 and 6. 18 and 19 represent a pair of slotted wire holding pins and 20 and 21 two bights of the wire 22. 23 indicates a groove in the cylinder 7, 24 a single tooth carried by said cylinder, 25 a gear with which said tooth 65 engages, 26 a shaft on which said gear is mounted, and 27 a cutter disk having the cutter teeth 28 and 29 rigid with the gear 25, as will be best understood from Figs. 1 and 10. 70

30 represents a hook pivoted to the member 13 as at 31, and provided with the curved hand operated extension 32. Said hook member 30 is also provided with the extension 33 to which is pivoted as at 34 the 75 reciprocating pusher member 35 having the flat extending lip 36 underlying the end 37 of the wire, and also having the bent portion 38 positioned behind said end, all as will be clear from Figs. 3^a and 4. As best 80 shown in Fig. 5, the wire 22 near one end is provided with a flat portion and shoulder 41. The slotted holding post 18, as best 85 shown in Fig. 9, is provided with the tapered opening 42 leading to the straight slot 43, of a dimension to accommodate the outer bight 21 of the wire, and with the inner slit 44 of a dimension sufficient to only accommodate the flat portion 40 of the wire. In other words, the machine is provided 90 with any suitable means having two open ended slots, one of which is a slit with a width slightly greater than the thickness of the reduced portion of the wire, but less than the normal diameter of said wire, while 95 the other is a slot of a width slightly greater than said normal diameter of the wire. The open ends of the slots enable the user to readily insert into the same and to withdraw therefrom, not only the deformed end 100 of the wire, but also the bight of said wire which latter feature greatly facilitates the operation of banding boxes. As will be clear from Figs. 6, 8, and 10, the shaft 3 has keyed thereto the cylindrical member 105 50, which member is slotted or cut out to accommodate the pawls 51 and 52 mounted on the common shaft 53 and controlled by

the springs 54 and 55 respectively. Surrounding said member 50 is the above mentioned spiral gear 4, having on its interior the notch 56 with which the pawl engages 5 when the shaft 3 is turned in one direction. And also surrounding said member 50 is the hollow extension 58 provided with the notch 59 with which the pawl 52 engages when said shaft 3 is turned in an opposite 10 direction.

The operation of this machine is as follows. The flat surface 65 of the frame 1, is laid flat down upon the package to be wired, whereupon the hand readily lifts the gravity actuated hook 30 and inserts the flat portion 40 of the wire into the slit 44 of the post 18, where it is held by reason of the shoulder 41 on the end 37, contacting with said post. The bight 20 of said wire is now passed into 15 the tapered slots 15 of the feet or lugs 11 and 12, and into the slots 16 and 17 of the wire twisting gear 9, thence through the slot of post 19, and under the tensioning post 6, around the box 66 and back under gravity 20 actuated hook 30. From the hook 30 the bight 21 passes into the larger slot 43 of the post 21, into the slots 15, 16, and 17 as before, into the slot of post 19, and into the slot 67 25 of the tensioning post 6. Gravity actuated latch or hook 30 thus serves to hold the bights 20 and 21 in their parallel relations during the tensioning and twisting operations. Said slot 67 is surrounded by the helical rib 68 behind which the bight 21 passes, and the 30 turning of which holds said bight well in said slot. The handle 69 may now be turned in the proper direction to make the pawl 51 engage the notch 56, whereupon the spiral gear 4 will rotate the spiral gear 5 and thus 35 will the tensioning post 6 be rotated to tighten the wire around the box 66. The wire 20 being thus put under tension, and the spiral gears 4 and 5 being mutually self-locking, it will be automatically held under tension 40 while the rotation of shaft 3 is reversed, without letting go of the handle 69, and the pawl 52 made to engage the notch 59 in the hollow extension 58 of the cylinder 7. Thus 45 are the said cylinder, gear 8 and slotted gear 9 rotated, to twist the bights 20 and 21 together. It will be observed that said bights are held against rotation by the posts 18 and 19, that the slots 15 and 16 are large enough 50 to permit said bights to rotate therein, and that the slot of the gear 19 is so narrow that it causes said bights to rotate around the center of said gear, with the result that a twisted tie of great strength is produced.

After leaving said post 19, as will be clear 55 from Figs. 1 and 10, the bight 20 passes downwardly while the bight 21 passes upwardly, and owing to this separation, one of the cutters 28 and 29 severs said bight 21 the instant the twisting operation is completed. That is to say, the tooth 24 turns the

gear 25, 60° for each rotation of the shaft 3, and therefore after three twists have been put in the bights, one of the cutters is brought into its severing position. After the bight 21 is thus severed, a throw of the hand 70 strikes the extension 32, which lifts the hook 30, and causes the pusher member 38 to force the flat portion 40 out of the slit 44, while the severed end of the wire is readily removed from the tensioning post 6. 75

In the somewhat modified form of gear and cutter illustrated in Figs. 2 and 3, the cylinder 7 is provided with the tooth 70 of the shape shown, while the "Geneva stop" mechanism 71 is substituted for the gear 25, 80 and the gear teeth 73 and 74 are somewhat hooked shaped. Otherwise, the parts are, or may be, the same as previously described in connection with Figs. 1 and 10.

It will now be clear that by flattening the 85 end of the wire 22 in the manner disclosed, the owner of the machine is enabled to induce the user to employ only that high grade of wire that is furnished him, and thereby to prevent the failures and bad knots 90 which often result from the use of wire not of a suitable quality for this kind of work. In other words, the user cannot himself readily flatten the ends 37 of the binding wires, and ordinarily he would not take 95 the trouble to do it if he could. The owner of the machine, on the other hand, can readily flatten said wire ends while they are passing through the machine, (not shown) that cuts the wires into suitable lengths. Of course, it follows that without flattening 100 said ends 37 said user cannot hold them in the machine during the tensioning operation.

It will also be clear that this machine not only thus partially guarantees that the user 105 will employ a certain kind of high grade wire that is furnished him, but it affords a mechanism which is unusually quick and efficient in action. For the shaft 3 may be

reversed from its tensioning operation into 110 its wire twisting operation in a minimum of time, and the extension 32 of the hook 30 enables a swift movement of the hand to disengage the end 37 of the wire from the post 18 also in a minimum of time. The feet, or lugs 11 and 12 of the machine afford 115 a means for preventing the machine from lifting, or tilting, during the twisting operation, and the rear frame extension 90, not only affords a means for holding the machine by hand down to its work, but also a space for a name plate 91. The entire frame is comparatively light in weight so that the machine can be readily lifted and applied to the package. The tapered slots 15 in the feet 11 and 12 greatly facilitate the entering 120 of the wire bights into said slots, while the downward inclination of said slots render it an easy matter to slip the said feet 11 and 12 from under the finished, twisted knot. 125

130

It will also be clear that instead of flattening the end of the wire as illustrated in Fig. 5, said wire may be only reduced in diameter or rounded over the portion 40. As a matter of fact, when a wire is compressed in such manner as to thus reduce its diameter, it is hardened, and therefore has a greater tensile strength than the soft portions of the wire. Of course, such rounded portions would be provided with the same holding shoulders as is the case in Fig. 5. A convenient way of making these rounded reduced sections as well as of making the flattened reduced sections 40 is to provide an attachment to the cutting machine so that as portions of coiled wire are passed through said cutting machine to sever said portions into convenient lengths, said attachment will reduce the cross section of the wire near the end to be cut off. Further, if it is desired to have each end of the cut off wire reduced in cross section as illustrated in Fig. 5, two attachments will be placed on the cutting machine, on each side of the rounded portion 37 shown in Fig. 5, and two reduced portions 40 will be thus put into the wire while the cutting will be done, at or near the middle of the unreduced portions 37. By this means each section of wire that encircles the package will have each end provided with a reduced portion 40 which may be either flat, round or of any other cross section.

It is obvious that those skilled in the art may vary the details of construction as well as the arrangement of parts without departing from the spirit of the invention, and therefore it is not desired to be limited to the above disclosure except as may be required by the claims.

What is claimed is:—

1. In a wire tying machine, the combination of a frame; an operating shaft; a wire tensioning means; a wire twisting means; and connections between said shaft and said wire tensioning, and wire twisting means, whereby upon turning said shaft in one direction the wire will be tightened and by reversing the motion of said shaft the wire will be twisted, substantially as described.

2. In a wire tying machine, the combination of a frame; an operating shaft; a wire tensioning means, a wire twisting means; and connections comprising a pair of oppositely disposed pawls between said shaft and said wire tensioning, and wire twisting means, whereby upon turning said shaft in one direction the wire will be tightened and by reversing the motion of said shaft the wire will be twisted, substantially as described.

3. In a wire tying machine, the combination of a frame; an operating shaft; a wire tensioning means; a wire twisting means; and connections comprising a pair of self

locking gears and a pair of oppositely disposed pawls between said shaft and said wire tensioning, and wire twisting means, whereby upon turning said shaft in one direction the wire will be tightened and by reversing the motion of said shaft the wire will be twisted, substantially as described.

4. In a wire tying machine, the combination of a frame; an operating shaft; a wire tensioning means; a wire twisting means; a wire cutting means; and connections between said shaft and said wire tensioning, and wire twisting means, whereby upon turning said shaft in one direction the wire will be tightened and by reversing the motion of said shaft the wire will be twisted and severed, substantially as described.

5. In a wire tying machine, the combination of a frame; an operating shaft; a wire tensioning means; a wire twisting means; a wire cutting means comprising a gear; means to drive said gear and rotating said cutter; and connections between said shaft and said wire tensioning, and wire twisting means, whereby upon turning said shaft in one direction the wire will be tightened and by reversing the motion of said shaft the wire will be twisted, substantially as described.

6. In a wire tying machine, the combination of a frame; a wire twisting means; and wire holding means in said frame provided with a slit of a width less than the diameter of said wire adapted to receive and hold a flattened portion of the wire during the twisting operation, substantially as described.

7. In a wire tying machine, the combination of a frame; a wire twisting means; and wire holding means in said frame comprising a post having a slit of a width less than the diameter of said wire adapted to receive and hold a flattened portion of the wire during the twisting operation, substantially as described.

8. In a wire tying machine, the combination of a frame; a wire twisting means; and a wire holding means provided with a slit of a width less than the diameter of said wire adapted to receive a flattened portion of the wire and with a slot adapted to receive a round portion of a bight of said wire, substantially as described.

9. In a wire tying machine, the combination of a frame; a wire twisting means; a wire holding means provided with a slit to receive a flattened portion of the wire and with a slot adapted to receive a round portion of a bight of said wire; a wire tensioning means adapted to receive said bight; and a shaft and connections for operating said wire twisting and tensioning means, substantially as described.

10. In a wire tying machine, the combination of a frame; a wire twisting means; a

wire holding means provided with a slit to receive a flattened portion of the wire and with a slot adapted to receive a round portion of a bight of said wire; and means to force said flattened portion out of said slit when the twisting operation is completed, substantially as described.

11. In a wire tying machine, the combination of a frame; a wire twisting means; a wire holding means provided with a slit to receive a flattened portion of the wire and with a slot adapted to receive a round portion of a bight of said wire; a severing means; and means to force said flattened portion out of said slit after the twisting and severing operations, substantially as described.

12. In a wire tying machine, the combination of a frame; a wire twisting means; a wire holding means provided with a slit to receive a flattened portion of the wire and with a slot adapted to receive a round portion of a bight of said wire; a tensioning means; a severing means; and a reciprocating means adapted to force said flattened portion out of said slit after said severing means has been operated, substantially as described.

13. In a wire tying machine, the combination of a wire twisting means; a slotted forwardly projecting foot; means to hold a flattened end of the wire; a hook to hold a bight of said wire; and an extension of said hook adapted to be struck by the hand to release said bight, substantially as described.

14. In a wire tying machine, the combination of a wire twisting means; a slotted forwardly projecting foot adapted to steady the machine during the twisting operation; means to hold a deformed end of the wire; a wire tensioning means; a severing means; a hook to hold a bight of said wire; and an extension of said hook adapted to be struck by the hand to release said bight, substantially as described.

15. In a wire tying machine, the combination of a wire twisting means; a slotted forwardly projecting foot adapted to steady the machine during the twisting operation; means to hold a deformed end of the wire; a wire tensioning means; a severing means; a single shaft operating said twisting tensioning and wire severing means; a hook to hold a bight of said wire; and an extension of said hook adapted to be struck by the hand to release said bight, substantially as described.

16. In a wire tying machine, the combination of a frame provided with a handle by which the machine may be lifted, an extension by which it may be held down to the work and adapted to receive a name plate and with a pair of forwardly extending slotted feet, in combination with a wire twist-

ing means; a wire tensioning means; and a shaft adapted to operate both of said twisting and tensioning means, substantially as described.

17. In a wire tying machine, the combination of a frame provided with a handle by which the machine may be lifted, an extension by which it may be held down to the work and adapted to receive a name plate and with a pair of forwardly extending slotted feet, in combination with a wire twisting means; a wire tensioning means; a shaft adapted to operate both of said twisting and tensioning means; a wire holding means provided with a slit adapted to hold a flattened portion of the wire; and means to force said flattened portion out of said slit after the twisting operation, substantially as described.

18. In a wire tying machine, the combination of a frame provided with a handle by which the machine may be lifted, an extension by which it may be held down to the work and adapted to receive a name plate and with a pair of forwardly extending slotted feet, in combination with a wire twisting means; a wire tensioning means comprising spiral gears; a shaft associated with oppositely disposed driving pawls adapted to operate both of said twisting and tensioning means; a wire holding means provided with a slit adapted to hold a flattened portion of the wire; means to force said flattened portion out of said slit after the twisting operation; a wire severing means; and a hook having a curved extension for holding and releasing said wire, substantially as described.

19. In a wire tying machine the combination of a wire twisting means; means of less dimensions than the cross section of the wire adapted to receive and hold a deformed portion of said wire; and means to hold and tension another portion of said wire prior to the twisting operation, substantially as described.

20. In a wire tying machine the combination of a frame adapted to receive two parallel disposed bights of a wire one of whose ends is provided with a deformed portion; means of less dimensions than the cross section of the wire adapted to receive and hold said deformed portion; means adapted to receive and hold the other end of said wire; and means adapted to twist together said bights, substantially as described.

21. In a wire tying machine the combination of a wire twisting means; means of less dimensions than the cross section of the wire adapted to hold a deformed end of the wire during the twisting operation; and means for holding and tensioning the other end of said wire prior to the twisting operation, substantially as described.

22. In a wire tying machine, the combination of a frame; a wire twisting means; and a wire holding means in said frame provided with a pair of open ended slots, one of which has a width less than the normal diameter of said wire, and the other of which has a width greater than said normal diameter, said last named slot adapted to receive a bight of said wire prior to the twisting operation, substantially as described.
23. In a wire tying machine, the combination of a frame; a wire twisting means; and a wire holding means provided with a slot of a width less than the normal diameter of the wire adapted to receive a flattened portion of said wire, and said holding means also provided with an open ended slot of a width greater than the normal diameter of the wire adapted to receive a bight of said wire, substantially as described.
24. In a wire tying machine, the combination of means of less width than the normal cross section of the wire adapted to receive and hold a deformed portion of said wire, and means to hold and tension another portion of said wire prior to the twisting operation, substantially as described.
25. In a wire tying machine, the combination of a frame adapted to receive two parallel disposed bights of a wire one of whose ends is provided with a reduced portion; means carried by said frame having a slot of a less dimension than the normal diameter of said bights adapted to receive and hold said reduced portion; means adapted to hold the other end of said wire; and means adapted to twist together said bights, substantially as described.
26. In a wire tying machine the combination of a wire twisting means; means of a less width than the normal cross section of the wire adapted to receive and hold a deformed end of the wire during the twisting operation; and means for holding and tensioning the other end of said wire prior to the twisting operation, substantially as described.
27. In a wire tying machine, the combination of a wire tensioning means; a wire twisting means; means provided with a slot of less width than the diameter of the wire for receiving and holding a deformed portion of the wire prior to the tensioning operation; and means for receiving and holding another portion of said wire prior to the twisting operation, substantially as described.
28. In a wire tying machine, the combination of means for exerting a tension on the wire; means comprising a slotted post and pinion for twisting said wire while under tension; and means slidably longitudinally of said post adapted to positively disengage the twisted wire from said post upon the completion of the twisting operation, substantially as described.
29. In a wire tying machine the combination of means for exerting a tension on the wire; means comprising a holding post and a slotted pinion for twisting said wire while under tension; means adapted to automatically sever said wire at the end of the twisting operation; and means movable longitudinally of said post adapted to positively disengage the twisted wire from said post after the completion of the twisting operation, substantially as described.
30. In a wire tying machine, the combination of means for tensioning a wire; means for twisting said wire while under tension; means comprising a stationary slotted element, through which said wire passes to hold said wire during the twisting operation; means slidable longitudinally of said slotted element to positively disengage the wire from said element after the twisting operation; and means comprising a lever for operating said slidable wire disengaging means.
31. In a wire tying machine, the combination of a holding post adapted to receive two bights of a wire to be twisted; a gravity actuated latch normally holding said bights in said post; and means operated by said latch for forcibly ejecting said bights after the twisting operation, substantially as described.
32. In a wire tying machine, the combination of a holding post adapted to receive two bights of a wire to be twisted; a latch pivoted at one extreme end of the machine normally holding under the action of gravity said bights in said post; and means operated by said latch for forcibly ejecting said bights after the twisting operation, substantially as described.

In testimony whereof we affix our signatures.

ALEC J. GERRARD.
PARVIN WRIGHT.
